UNITED STATES PATENT OFFICE.

ROBERT L. DORAN, OF CHICAGO, ILLINOIS.

OIL-BURNER.

1,197,720.

Specification of Letters Patent. Patented Sept. 12, 1916.

Application filed May 26, 1916. Serial No. 100,009.

To all whom it may concern:

Be it known that I, ROBERT L. DORAN, a citizen of the United States of America, and a resident of Chicago, county of Cook, and

5 State of Illinois, have invented certain new and useful Improvements in Oil-Burners, of which the following is a specification.

The main objects of this invention are to provide an improved form of combined gas 10 generator and burner for utilizing heavy fuel oils for heating and cooking; to provide an improved arrangement of the parts whereby the device is particularly suitable for use in the fire box of coal and wood 15 stoves and ranges; to provide an improved form of burner; to provide an improved arrangement of the generator; to provide improved means for simultaneously controlling the flow of oil to the generator and the flow 20 of vapor from the generator to the mixing chamber; and to provide improved means for controlling the admission of gas to the burner.

An illustrative embodiment of this invention 25 is shown in the accompanying drawings, in which:

Figure 1 is a perspective view of the complete device. Fig. 2 is an enlarged sectional plan of the upper burner, some of the parts 30 below being omitted for the sake of clearness. Fig. 3 is a side elevation of one of the mixing chambers. Fig. 4 is a sectional view of the same taken on the line A—A of Fig. 3. Fig. 5 is an enlarged transverse sectional 35 elevation of the device shown in Fig. 1. Fig. 6 is a longitudinal sectional elevation of the side burner. Fig. 7 is an enlarged horizontal sectional detail of the oil supply fitting and the main generator tube. Fig. 8 is a longitudinal sectional elevation of the arrangement 40 illustrated in Fig. 1. Fig. 9 is an enlarged transverse sectional elevation of the device, taken in the opposite direction from that of Fig. 5.

45 In the construction shown in the drawings, the device comprises a pair of standards 1 and 2 upon which are mounted a top or main burner 3, a side or oven burner 4, and their respective generating means 5 and 6. The parts are all arranged compactly 50 upon the standards 1 and 2, so that the device is particularly suitable for arrangement within the fire box of any of the usual coal or wood ranges whereby the upper

burner 3 is to be used for general cooking 55 on top of the stove, and the burner 4 is to be used for heating the oven for baking and roasting.

The top or general cooking burner 3 is in the form of a tubular oblong loop having a 60 plurality of slots 7 cut in the upper part thereof, through which the gas is emitted to be burned. A manifold in the form of a U-shaped pipe or tube 8 depends from the under side of the burner 3 and has the ends 65 thereof connected to opposite sides. A conduit 9 is attached at the bend of the U-shaped pipe 8 as shown in Fig. 2 and is bent back upon itself the same as shown in Fig. 8, and connects with the mixing chamber 10, 70 through which the gas is delivered to the burner 3.

The side or oven burner 4 is an oblong tubular member of substantially rectangular cross section, which has a series of slots 11 75 cut in the top and outer side through which the gas is emitted to be burned. A conduit 12 connects the burner 4 at one end with a mixing chamber 13 from which the gas is supplied. A tube 14 is supported within the 80 burner 4 and is attached to and forms a continuation of the conduit 12. The tube 14 is nearly coextensive with the interior of the burner, so that it terminates adjacent to the other end of the burner 4 and serves to conduct the gas to the farther end of the burner from which it travels back along the space 85 between the burner and the tube and escapes through the slots 11. This tube thus serves to more evenly distribute the gas along the 90 burner and prevent an excessive supply reaching any portion of the slots 11, as would be the case if the gas entered the burner direct at the end thereof which is connected to the conduit 12.

95 The generators 5 and 6 are preferably in the form of tubes and are supported in substantially the same horizontal plane, the tube 5 being located below the burner 3 and between the arms of the U-shaped pipe 8, 100 and the tube 6 being located above and slightly to one side of the burner 4. The generators are supported by having at one end threaded connections with the oil supply fittings 15 and 16 respectively, and at the 105 opposite ends having sliding or telescopic engagement with the respective mixing chambers 10 and 13. This permits the tubes 5

and 6 to be unscrewed from the respective fittings 15 and 16, so as to be quickly removed from the device for the purpose of cleaning or for replacing new ones. The ends of the tubes 5 and 6 are each provided with an orifice as at 17, Fig. 7, which orifices are located wholly within the respective mixing chambers 10 and 13 and in alignment with the open ends of the respective conduits 9 and 12, as will be more clearly observed from Fig. 4.

Auxiliary burners 18 and 19 are arranged adjacent to the respective generators 5 and 6. The burner 18 is an oblong hollow member of substantially inverted T-shaped cross section having slots 18.1 formed in the end of the stem part through which gas is emitted and burned. The burner 18 is supported within the bend of the U-shaped pipe 8 directly below the generator 5, so that it is adapted to keep the generator heated for the purpose of vaporizing the fuel oil. A nipple connection 20 provides communication with the pipe 8 for the purpose of supplying gas to the burner. The nipple 20 has a semi-cylindrical deflector 21 depending therefrom into the U-shaped pipe 8 and opposed to the open end of the conduit 9. This deflector insures a sufficient quantity of gas being directed to the burner 18. Channels or troughs 22 are formed in the transverse parts of the burner 18 and are adapted to receive a quantity of oil to be burned for the purpose of preheating the generator 5 when it is desired to start the operation of the device. A quantity of non-combustible absorbent packing may be placed in the troughs 22, which is found to improve the burning of the oil for purposes of pre-heating.

The auxiliary burner 19 is arranged at one side of the generator 6 between it and the generator 5, and is connected by a nipple 23 to the pipe 8 so that during the operation of the top burner 3, gas is supplied to the auxiliary burner 19 whereby the generator 6 is kept sufficiently heated so that upon the admission of oil to the generator gas will be produced in sufficient quantity to permit the burner 4 to be started. A slit 24 is formed across the top and the back side of the burner 19, through which a film of gas is emitted to permit an ignition from the burner 18 to carry across to the gas emitting from the slots 25 in the front face of the burner 19, which in turn will ignite the gas emitting from the slots 11 in the burner 4.

The mixing chambers 10 and 13 are in the form of inverted L's, each having a nipple 26 depending therefrom, which forms the inlet for air that is to be mixed with the vapor discharged through the orifices in the ends of the generators 5 and 6. These L's are supported in place by reason of

their connection to the generators and the respective conduits 9 and 12.

The fittings 15 and 16 are connected together by a tube 27 and the former is connected to an oil supply by means of a pipe 28. Valves 29 and 30 are arranged in the fitting 15 so as to control the supply of oil to the respective generators 5 and 6. The valve 29 has a tapered end 31 which coacts with a seat 32 for controlling the supply of oil to the generator 5. A rod 33 is integrally attached to the valve 29 and extends longitudinally through the generator 5 and has a needle valve 34 formed on the end thereof which controls the orifice 17. By virtue of this arrangement of the valves 29 and 34, the supply of oil to the generator 5 and the discharge of vapor therefrom is simultaneously controlled. The valve 30 is of the usual needle type, as is clearly indicated in Fig. 7, and controls the admission of oil to the generator 6.

The burner 3 has transverse partitions 35 and 36 located adjacent to the openings connecting with the ends of the pipe 8, but arranged on respectively opposite sides of said openings. These partitions subdivide the interior of the burner into chambers 37 and 38 communicating respectively with the opposite ends of said pipe 8. A valve seat 39 is formed in the burner 3 adjacent to one of the openings leading to the pipe 8 with which a valve 40 coacts for controlling the admission of gas from the corresponding end of said pipe to the respective chamber, 100 in this case the chamber 38. A stem 41 carries the valve 40 and extends to the exterior of the burner and affords means of shifting the valve 40.

The device is intended to be set in the fire box of the stove with the burner 4 facing the partition which separates the fire box from the oven. In order to insure proper spacing of the burner 4 away from the stove lining, pins or shoulders 42 protrude from the face of the burner in such manner as to contact with said stove lining.

The operation of the device shown is as follows: To start the device, a quantity of oil or alcohol is poured into the troughs 22 and ignited, then as it burns it heats the generator 5. When the generator 5 has become sufficiently heated, the oil is turned on by means of the valve 29, so that the oil enters the generator; whereupon it is converted into a vapor and flows through the orifice 17 into the mixing chamber 10, conduit 9, and pipe 8. On entering the pipe 8, a portion of the gas is deflected by the deflector 21 into the burner 18, whereby the heating of the generator is continued. The gas also ascends the pipe 8, enters the chambers 37 and 38 of the burner 3 and is ignited as it is emitted from the slots 7. By shifting the valve 40, one of the chambers may

have the supply of gas cut off therefrom, so that only one half of the burner will be in operation. The auxiliary burner 19 is also supplied with gas from the one arm of the pipe 8, and the gas flowing from the transverse slot 24 is ignited by the burner 18 and accordingly ignites the gas issuing from the slots 25. The auxiliary burner 19 keeps the generator 6 heated so that when it is desired to use the oven burner 4 it is only necessary to open the valve 30 and allow the oil to be supplied to the generator 6. By means of the pipe 14, the gas is conveyed to the farther end of the burner 4 and then it passes into the space within the burner 4 surrounding the pipe 14.

It is intended that the oven burner 4 should be used only for the purpose of heating the oven to the proper degree for baking, and when the oven is thoroughly heated and the baking started the oven burner may be shut off since the top burner will maintain the heat sufficiently to finish the baking.

Although but one specific embodiment of this invention has been herein shown and described, it will be understood that numerous details of the construction shown may be altered or omitted without departing from the spirit of this invention as defined by the following claims.

I claim:—

1. The combination of a horizontally disposed burner in the form of a tubular loop, a depending manifold connected to opposite sides of said burner, a mixing chamber, a generator tube located below said burner between the arms of said manifold and connected to said mixing chamber, a conduit connecting said mixing chamber with said manifold, an auxiliary burner supported between the arms of said manifold below said generator, and a connection between said manifold and auxiliary burner.

2. The combination of a horizontally disposed burner in the form of a tubular loop, a depending manifold connected to opposite sides of said burner, a mixing chamber, a generator tube located below said burner between the arms of said manifold and connected to said mixing chamber, a conduit connecting said mixing chamber with said manifold, an auxiliary burner supported between the arms of said manifold below said generator, a connection between said manifold and auxiliary burner, and a deflector depending from said connection into said manifold and opposed to the end of said conduit.

3. The combination of a horizontally disposed burner in the form of a tubular loop, a depending manifold connected to opposite sides of said burner, a mixing chamber, a generator located adjacent to said burner, a conduit connecting said mixing chamber with said manifold, partitions extending

across the interior of said burner at opposite sides of the burner adjacent to the connections of said manifold with said burner, but on diagonally opposite sides thereof, a valve seat in one of said chambers adjacent to the connection of said manifold therewith, a valve shiftably mounted in said burner so as to coact with said seat for controlling communication between said manifold and the respective burner chamber; and a rod connected to said valve and extending to the exterior of said burner.

4. The combination of a pair of standards, an oil burner mounted on top of said standards, a second oil burner secured to the sides of said standards below said top burner, mixing chambers for the respective burners, separate generator tubes arranged adjacent to each of said burners and connected to said mixing chambers, conduits connecting the mixing chambers with the respective burners, auxiliary burners arranged adjacent to each of said generators, and pipes connecting both of said auxiliary burners to one of said conduits.

5. The combination of a pair of standards, an oil burner mounted on top of said standards, a second oil burner secured to the sides of said standards below said top burner, mixing chambers for the respective burners, separate generator tubes arranged adjacent to each of said burners and connected to said mixing chambers, conduits connecting the mixing chambers with the respective burners, auxiliary burners arranged adjacent to each of said generators, and pipes connecting both of said auxiliary burners to the conduit connecting with said top burner.

6. The combination of a pair of standards, an oil burner mounted on top of said standards, a second oil burner secured to the sides of said standards below said top burner, mixing chambers for the respective burners, separate generator tubes disposed in substantially the same horizontal plane and connected to the respective mixing chambers, one of said generator tubes being located directly under the said top burner and the other over said side burner, conduits connecting said mixing chambers with the respective burners, auxiliary burners for said generator tubes arranged under and at the side of the respective generator tubes, and branch pipes connecting both of said auxiliary burners with the conduit leading to said top burner.

7. The combination of a pair of standards, an oil burner mounted on top of said standards, a second oil burner secured to the sides of said standards below said top burner, mixing chambers for the respective burners, separate generator tubes disposed in substantially the same horizontal plane and connected to the respective mixing chambers, one of said generator tubes being located di-

rectly under the said top burner and the other over said side burner, conduits connecting said mixing chambers with the respective burners, auxiliary burners for said generator tubes arranged under and at the side of the respective generator tubes, branch pipes connecting both of said auxiliary burners with the conduit leading to said top burner, and means on one of said auxiliary burners adapted to cause it to be ignited from the other auxiliary burner.

Signed at Chicago this 17th day of May, 1916.

ROBERT L. DORAN.
